WARNING SIGNAL SYSTEM

Dock R. Wheeler, Lake Charles, La.

Application April 6, 1939, Serial No. 266,370

2 Claims. (Cl. 200—106)

My invention relates to signalling systems, and has among its objects and advantages the provision of a system particularly adapted to buildings such as hotels and the like for signalling fires and unauthorized entry into the different rooms throughout the building, in addition to setting fire extinguishing machinery into operation as well as signalling fire departments, police stations and the like.

In the accompanying drawings:

Figure 1 is a front elevational view of a signal board incorporated in my system;

Figure 2 is a rear view of the structure of Figure 1;

Figure 3 is an elevational view of the mechanism inside the board illustrated in Figure 1;

Figure 4 is a detail view of a switch drop door incorporated in the board of Figure 1;

Figure 5 is a sectional detail view of one type of switch employed in the switch drop door of Figure 4;

Figure 6 is a sectional view of another type of switch associated with the door of Figure 4;

Figure 7 is a detail view of a portion of one of the switch parts;

Figure 8 is a sectional view of one of the lamp units;

Figure 9 is a face view of a portion of the signal structure;

Figure 10 is a view of a different signal lamp;

Figure 11 is a face view of another signal unit;

Figure 12 is a sectional view of one of the switch mechanisms; and

Figure 13 is a diagrammatic view of the circuit generally.

In the embodiment selected to illustrate my invention, I make use of a cabinet 10 having a door 12 hingedly connected at 14 with the cabinet. Door 12 is provided with a vertical bar 16 for ornamental purposes, which bar is located intermediate the vertical sides of the cabinet. Door 12 includes a glass face 18 and the door includes side walls 20, a bottom wall 22 and a top wall 24 arranged to have edge-to-edge relation with the corresponding walls 26, 28 and 30, respectively, of the cabinet structure illustrated in Figure 3. Door 12 is provided with a vertical partition 32 having its ends connected with the walls 22 and 24 intermediate their ends so as to provide chambers 34 and 36 designated "fire" and "burglar," respectively, as indicated at 38 and 40 in Figure 1. Above the wall 30 of Figure 3, I provide a chamber 42, and the door 12 is provided with a facing 44 which covers the chamber 42. Facing 44 is provided with a small

5 door 46, which door is provided with a cloth covered opening 48 across which extends three ornamental bars 50. Inside the chamber 42 I mount a bell 52 and a buzzer 54. Bell 52 is associated with the fire chamber 34, while the buzzer 54 is associated with the burglar chamber 36.

Door 12 is provided with a partition 56 which parallels the glass face 18 but is spaced therefrom as illustrated in Figure 8. Partition 56 is associated with each of the chambers 34 and 36. Figure 1 illustrates the chamber 34 as being provided with identifying numerals 58 running from 1 to 20. Chamber 36 is provided with similar identifying numerals 60 which also run from 1 to 20. The numerals 58 and 60 may be printed on the glass 18 and are located directly in front of electric lamps 62. Each identifying numeral is associated with one lamp 62. All the lamps are of the same type and mounted in the same manner so that the description of one lamp mounting will apply to all.

Figure 8 illustrates one of the lamps 62 and the mounting therefor. Wall 56 is provided with an opening 64 in which I position a collar 66 having internal threads 68. Collar 66 is fixedly secured to the partition 56 by bolts 70 which pass through openings in the flange 72 and are threaded into the partition. One of the electric lamps 62 is supported axially of a sleeve 76 threaded at 78 for connection with the collar 66. Lamp 62 includes a contact sleeve 80 fitting snugly in an insulating collar 82 threaded into the neck 84 of a partition 86 inside the sleeve 76. An insulating washer 88 is mounted on the collar 82 adjacent the neck 84 and is clamped against the latter through the medium of a contact flange 90 having a neck 92 threadedly related to the contact sleeve 80. Flange 90 abuts the insulating washer 88 and draws the sleeve 94 of the electric lamp against the insulating washer 82 as it is turned down on the threaded sleeve 80.

To the flange 90 I connect an electric wire 96, and the central terminal 98 of the electric lamp is arranged to engage a spring conductor 100 having its end 102 fixedly secured through the medium of the terminal screw 104 anchored to the sleeve 76, but insulated therefrom. The second electric wire is illustrated at 106 as being electrically connected with the spring conductor 100. One end of the sleeve 76 carries a felt washer 108 arranged in engagement with the inner face of the glass 18. Because of the ring 108, the light rays from the lamp 62 is confined

inside the light chamber 110 which is aligned with the identifying indicia 58 associated with that lamp. Thus each lamp is associated with an individual light compartment sealed from the other compartments so that an illuminated lamp will clearly illuminate the identifying indicia associated therewith. In other words, the lamps 62 in the chamber 34 designate the rooms in the building, which is also true of the lamps in the chamber 36.

The sleeves 76 are removably mounted on the partition 56, and an effective light-tight relation is established between the sleeves and the glass 18 by turning the sleeves tightly against the rings 108. Thus all the sleeves are individually 16 accessible by merely swinging the door 12 to an open position.

Inside the cabinet structure of Figure 3 I mount a switch mechanism 112 in association with the chamber 34 and a switch mechanism 114 in association with the chamber 36. The mechanisms are identical in construction and operation so that the description of one will apply to both. Referring to Figures 3 and 4, a frame 116 is arranged vertically in spaced relation with one of the side walls 26. In association with the frame 116 I provide a drop frame 118, which is hingedly mounted at 120 with the lower end of the frame 116. Figure 3 illustrates the normal relation between the frame 116 and the drop frame 118, but 30 Figure 4 illustrates the drop frame 118 swung outwardly and downwardly 180 degrees for the purpose of illustrating the specific construction of the two frames.

Specifically, frame 116 includes four upright bars 122 interconnected at their lower ends by a frame member 124 and at their upper ends through the medium of frame members 126. Drop frame 118 also comprises four bars 128 connected into a unitary structure through the medium of cross frame members 130 and 132. Drop frame 118 is of the same configuration and proportions as the frame 116. Figure 3 illustrates the frame 116 as being provided with a lever 134 pivoted thereto at 136, which lever includes a hook 138 for connection with a hook 140 carried by a bar 142 associated with the drop frame 118. To the drop frame 118 I connect a sleeve 144 which slidably receives the bar 142, and the sleeve is provided with a set screw 146 for securing the bar 142 in different positions. Engagement between the hooks 138 and 140 supports the frames 116 and 118 in the manner illustrated in Figure 3, and the frame 118 is biased away from the frame 116 through the medium of a tension spring 148. Frame 118 may be released for movement away from the frame 116 by moving the lever 134 downwardly in the direction of the arrow 150 for bringing the hooks 138 and 140 out of holding relation. When the hooks are disengaged, frame 118 falls back a short distance, which distance is determined by the spacing between a resilient bumper 152 on the frame 118 and a bumping wheel 154 carried by a lever 156 pivotally connected at 158 with an upright frame 160 fixedly related to the wall 28.

On the bars 122 I mount a plurality of switches 162, three switches 164 and one switch 166. Switches 164 and 166 are arranged in a row transversely of the frame 116 at its bottom end. There are twenty of the switches 162, which correspond to the number of the lamps 62 in the chamber 34 or the chamber 36. For the sake of definiteness, the present description will be directed to 70 75

the switches and circuits associated with the chamber 34.

Figure 5 illustrates the specific construction of the switches 162. A contact blade 168 is positioned between two insulating blocks 170. A resilient contact blade 172 is positioned between one of the blocks 170 and an insulating block 174. Blades 168 and 172 and the blocks 170 and 174 are provided with aligned openings for the 10 reception of insulating sleeves 176 through which I pass bolts 178 for connecting all the parts into a unitary structure. Thus the blocks 170 and 174 define a body 180 which is secured to one of the bars 122 for mounting purposes. One of the blocks 170 and the block 174, as well as the spring contact blade 172, are provided with aligned openings for the reception of an insulating sleeve 182 into which a terminal screw 184 is threaded to have conducting relation with the blade 168. A wire 186 is connected with the terminal screw 184. Similarly, the block 174 is provided with a threaded opening for the reception of a terminal screw 188 having conducting relation with the blade 172. A wire 190 connects with the terminal screw 188.

Blade 172 may be flexed into conducting relation with the blade 168. Such flexing is brought about by moving the drop frame 118 to the latched position of Figure 3. However, unlatching of the frame 118 frees the blade 172 so that it will move to the full line position of Figure 5. To consummate conducting relation between the blades 172 and 168, I provide the drop frame 118 with a plurality of switch arms 192 having heads 194 for engagement with the blades 172 for flexing the same into engagement with the blades 168 when the drop frame 118 is moved to its latched position. Switch arms 192 are fixedly and adjustably related to the bars 128 through the medium of nuts 196, so that the arms may be precisely adjusted with respect to their respective switches 162. Frame 118 is also provided with three switch arms 198 which are arranged in operative relation with the three switches 164. One of the bars 128 is provided with a switch arm 200 associated with the one switch 166. Switch 166 is identical in construction with the switches 162, but the switches 164 are differently constructed as illustrated in Figure 6.

Flexible blade 202 is anchored between insulating blocks 204 in the same manner as the blade 168, but the blade 202 is resiliently urged into pressure relation with a blade 206 fixedly anchored between one block 204 and a block 208. The wire 210 is electrically connected with the terminal screw 212 electrically related to the blade 202. Wire 214 is electrically connected with the terminal screw 216 which is electrically related to the blade 206. Blade 202 is flexed out of conducting relation with the blade 206 when the drop frame 118 is in the latched position of Figure 3. In other words, moving the drop frame to its latched position brings the switch arms 198 into pressure relation with the blades 202 for flexing the same away from the blades 206.

Inside the cabinet structure I mount two upright supporting posts 218, one post being associated with the chamber 34 and the other post with the chamber 36. Since the posts perform similar functions and are associated with the same mechanism, the description will be limited to the post in association with the structure of the chamber 34. Post 218 and the frame 116 carry a cross support 220 upon which I mount

an electric coil 222. Above the coil I position an armature 224 which carries a contact plate 226 arranged to be attracted by the coil 222 when the latter is energized. Armature 224 is pivotally connected at 228 with the post 218, and one end of the armature includes a pressure element 230 arranged in pressure relation with one end of the lever 134 for pivoting the same in the direction of the arrow 150. To the opposite end of the armature 224 and the cross support 220 I connect a tension spring 232 of sufficient tension to hold the armature 224 in the position of Figure 3, but the spring will yield when the coil is energized to permit the armature to be pivoted downwardly. A post 234 is provided with stop screws 236 which may be adjusted to control the pivotal movement of the armature 224. In the normal position of Figure 3, the armature 224 is held in contact with the upper stop screw 236 because of the spring 232. Lever 134 is urged in the direction of the arrow 238 by reason of a tension spring 240 having one end connected with the lever and its opposite end connected with a bracket 242. Spring 240 is of such tension as to pivot the hook end of the lever downwardly into the path of the hook 142 and for holding the opposite end of the lever in pressure relation with the element 230. Hooks 138 and 140 have cam ends 244 which have camming relation when the drop frame 118 is pushed home to the position of Figure 3 for consummating hooked relation between the two hooks.

Lever 156 is provided with a bracket 246 to which I connect one end of a tension spring 248, the opposite end of the spring being connected with a bracket 250 carried by the upright 160. A resetting shaft 252 is connected with the lower end of the lever 156 through the medium of a pin 254 slideable in a slot 256 in the lever. One end of the shaft 252 is provided with a knob 256 accessible from a position exteriorly of the cabinet for manipulation purposes. Figure 3 illustrates the lever 156 in the normal position. When the drop frame 118 is unlatched it falls 45 against the upper end of the lever 156, and the frame may be reset to the position of Figure 3 by exerting a pull on the resetting shaft 252. Such a pull will pivot the lever 156 about its axis 158 for pivoting the roller 154 to the right when viewing Figure 3, which movement pushes the drop frame home. Drop frame 118, when positioned according to Figure 3, holds all the switches 162 and the switch 166 closed and the switches 164 open. When the drop frame is unlatched, the frame permits all the switches 162 and the switch 166 to open and the switches 164 to close.

Projecting from the outer face of the plate 18 near its bottom are switch knobs 258, 260, 262, 264 and 266, all of which are grouped with the chamber 34. Each knob includes a pointer 268, and the plate 18 is labeled to define the functions of the switches. Figure 1 illustrates the switch knob 258 labeled "fire extinguisher," as illustrated at 270. Switch knob 260 is labeled "fire department," as illustrated at 272, while the switch knob 262 is labeled "call guest," as indicated at 274. Switch knob 264 is labeled "guest light," as indicated at 276, while the switch knob 266 is labeled "alarm cut-off," as at 278. I mark the plate 18 to read "off" and "on" for each of the switches 258 to 266, as indicated at 280 and 282, respectively.

Projecting from the outer face of the plate 75

18 in association with the chamber 36 are switch knobs 284, 286, 288, 290 and 292. Switch knob 284 is labeled "police call," as at 294, while switch knob 286 is labeled "call guest," as at 296. Switch knob 288 is labeled "guest light," as at 298, while switch knob 290 is labeled "alarm cut-off," as at 300. Switch knob 292 is labeled "wire cut-off," as at 302. Each of the knobs 284 to 292 is provided with a pointer 304, and each pointer is associated with "off" and "on" marking as at 306 and 308, respectively.

Legends 270 to 278 lie within the perimeter of a box 310 located adjacent the inner face of the plate 18. Similarly, the legends 294 to 302 lie within the perimeter of a box 312. Each box is provided with an electric lamp for illuminating the reading matter lying within its perimeter. Both boxes and the lamps associated therewith are identical in construction and operation so that the description of one will apply to both. Referring to Figure 10, box 310 includes a bar 314 which supports a lamp 316 connected with a base 318 supported by the bar 314. Electric wires 320 and 322 are electrically connected with the lamp 316. Box 310 includes T-shaped members 324 which are secured to the partition 56 and a flange 326 having its lower edge secured to the wall 22. Box 310 is slotted at 328 for the reception of bolts 330 carried by the T-irons 324 to permit adjustment of the box toward and away from the plate 18. Between the box and the plate 18 position a light sealing gasket 332 which confines the zone of illumination within the box 310.

A similar box 334 is associated with the chamber 34 for illuminating the area of the plate upon which the term "fire" is printed. Similarly, a box 336 is associated with the chamber 36 for illuminating the term "burglar." Boxes 334 and 336 are provided with lamps 338 and 340, respectively.

Figure 12 illustrates the specific construction of the switch associated with the knob 258, which construction is identical with the construction of the switches associated with the knobs 260, 262, 264, 266, 284, 286, 288, 290 and 292. The knob is connected with a shaft 342 to which the pointer 268 is fixedly connected. Shaft 342 includes a crank 344, and one end of the shaft is rotatably journaled at 346 in a wall 348 located in a common plane with the plate 18 at its lower end. The opposite end of the shaft 342 is rotatably supported by a bearing 350, and a tension spring 352 has one end connected with the crank and its opposite end connected with a bracket 354 which supports the bearing 350. Thus the spring 352 yieldingly holds the crank 344 in either of two positions as it is swung beyond dead center toward either of said positions. The wall 348 carries two stop pins 356 against which the finger 358 of the crank may strike for limiting the free movement of the crank.

To the inner face of the wall 348 I connect arms 360 and 362 provided with right-angular ends 364 and 366, respectively. A wire 368 is electrically connected with the arm 360, and a wire 370 is electrically connected with the arm 362. Fixedly connected with the inner end of the shaft 342 is a switch arm 372 which is fashioned with diverging elements 374 arranged to provide a groove within which the end 364 may lie. The switch arm is also provided with diverging elements 376 within which the end 366 may lie. Fingers 360 and 362 are so fashioned as to have slight pressure relation with the ele-

ments 374 and 376 so as to insure effective bridging relation with the switch arm 372. Figure 12 illustrates the switch closed.

Referring to Figure 13, room No. 1 is indicated at 378 and room No. 2 at 380. These rooms correspond to the lamps numbered 1 and 2, as indicated by the indicia 58 of Figure 1. Only two of the rooms are illustrated, since the rooms and wiring therefor are similar so that one or two rooms will sufficiently illustrate the circuits. Rooms 378 and 380 are each provided with a fire extinguisher 382 and a thermostatic switch 384. Wires 386 and 388 extend to all the rooms, and each thermostatic switch is wired to the line 386 by a wire 390. Figure 13 illustrates two of the lamps 62, which lamps are numbered 1 and 2, respectively. A wire 392 leads from the lamp No. 1 to the fire extinguisher 382 in room No. 1, while a wire 394 connects the fire extinguisher with the wire 388. Contact 396 associated with the thermostatic switch 384 in room No. 1 is electrically connected with the wire 392 through the medium of a wire 398. A wire 400 connects the lamp 62 with a source of current 402, which may comprise a battery. Wire 386 is also connected with the battery. It will thus be seen that closing of the switch 384 in room No. 1 will close the circuit through the lamp 62 which is numbered 1. Switch 384 is sensitive to temperature so as to close when the room is endangered by fire. Lamp 62 carrying the number 2 is connected with the wire 400 through the medium of a wire 404 and is also connected with a wire 406 which connects with a wire 408 leading to the contact 410 of the switch 384. Wire 408 connects with the fire extinguisher 382 in the room No. 2, and the fire extinguisher is connected with the wire 388 through a wire 412. Closing of the switch 384 closes the circuit through the No. 2 lamp 62.

Figure 13 illustrates the four bars 128 of the drop frame 118, but only the four upper switches 162 are illustrated for the sake of clearness. These bars are illustrated individually so as to more clearly illustrate their action. Figure 13 also illustrates the bars in the latched position of the drop frame 118. In addition to the four upper switches 162, I illustrate the three switches 164 and the switch 166. It will be noted that the four switches 162 are closed and that the three switches 164 are open, while the switch 166 is closed. Wire 190 of the switch 162 in the position 414 is connected with the wire 392 which leads to the fire extinguisher 382 in room No. 1. Similarly, wire 190 associated with the switch 162 in the 416 position is connected with the wire 406 which connects with the wire 408 leading to the fire extinguisher 382 in room No. 2. Wires 186 of the switches 162 are connected with a wire 418 which leads to the coil 222, which coil is connected with a wire 420 connected with a wire 422 connected with the wire 400 which connects with the battery 402. When the switch 384 in room No. 1 is closed, the circuit through the coil 222 is closed as follows: terminal 396, wire 398, wire 190, switch 162, wire 186, wire 418, coil 222, wire 420, wire 422, battery 402, wire 386, wire 390 and switch 384. Such energization of the coil 222 causes the armature 224 to be attracted thereto for kicking the hook 138 out of holding relation with the hook 140 to permit the drop frame 118 to be drawn outwardly from the frame 116 to a position at rest on the roller 154. Thus all the switches 162 will be opened through the energization of the coil 222 through closing of a switch 384 in any one of the rooms.

Assuming that the knob 258 has been turned for electrically connecting the wires 368 and 370 through the medium of the switch arm 372, the circuit through the fire extinguisher 382 in room No. 1 will be closed as follows: battery 402, wire 386, wire 390, switch 384, terminal 396, wire 398, wire 392, fire extinguisher 382, wire 394, wire 388, wire 368, switch arm 372, wire 370 and wire 422 back to the battery 402. Normally the fire extinguishing switch 424 remains closed so that the fire extinguisher 382 in the room No. 1 will be automatically set in operation when the switch 384 in that room is closed.

A motor driven attic fan 426 is connected with the wire 186 of the switch 166, and the wire 190 of this switch is connected with a wire 428 which connects with the wire 386. A wire 430 connects the motor of the fan 426 with the wire 422, so that the circuit through the motor of the attic fan 426 will be broken whenever the drop frame 118 is unlatched. Thus I automatically cut off the attic fan so as to prevent circulation of air during the fire emergency period.

Unlatching of the drop frame 118 closes all the switches 164. As the switch 164 in the 432 position is closed, the following circuit is energized: wire 214, wire 368 of the fire department switch 434 associated with the knob 260, assuming that the switch 434 is closed, wire 370 which leads to a fire department signal 436, a wire 438 connected with the wire 422, battery 402, wire 428 and wire 210 back to the switch 164 in the 432 position. Switch 434 may remain open to be manually closed, if necessary, when there is a fire in any one of the rooms. When the switch 164 in the 440 position is closed, the following circuit is completed: wire 214, the motor of a force pump 442, a wire 444 connected with the wire 422, battery 402, wire 428, wire 210 back to the switch 164 in the 440 position. When the switch 164 in the 446 position is closed, the following circuit is made: wire 214, wire 448, alarm 52, wire 450, wire 368 of the switch 452 associated with the knob 266, wire 370 connected with the wire 422, battery 402, wire 454, wire 210 back to switch 164 in the 446 position. Thus the alarm 52 will be sounded immediately upon dropping of the frame 118, assuming that the switch 452 is closed. In addition, the circuit through the lamps 316 and 328 will be closed with the closing of the switch 164 in the 446 position for illuminating the boxes 310 and 334 associated with the chamber 34.

The switch 456 associated with the knob 264 has its wire 370 connected with the wire 422 and its wire 368 leading to a lamp 458 which illuminates an arrow 460 indicating the location of the fire escape. Lamp 458 is connected with a wire 462 connected with a wire 464 attached to the wire 448. It will thus be seen that lamp 458 will be illuminated when the switch 456 is closed, assuming that the drop frame 118 is unlatched so that the switch 164 in the 446 position is closed.

In association with the lamp 458 I provide an audible signal 466 which is connected with the wire 464 and the wire 368 of the switch 468 associated with the knob 262. The signal 466 may be actuated through closing of the switch 468 under the conditions applying to switch 456. A lamp 470 is wired to the wire 464 and the wire 368 of the switch 456 in the same manner as the lamp 466 for illuminating a sign reading "small fire," as at 472. An audible signal 474 is connected with the wire 464 and the wire 368 associated with the switch 468. Thus closing of the switch 456 will illuminate both lamps 458 and 470, while clos-

ing of the switch 468 will close the circuits through the audible signals 466 and 474.

Figures 9 and 11 illustrate the indicating boards associated with the lamps 458 and 470 and the signals 466 and 474. Figure 9 illustrates the audible signal 466 as being associated with the lamp 458, both of which are enclosed within a box 476 which may be located in the building in the most advantageous position. The glass front 478 is provided with the reading "fire escape," as indicated at 480, and the arrow 460 appears on the glass 478 so that both the arrow and the reading matter will be illuminated.

Figure 11 illustrates the board associated with the lamp 470 and the signal 474. The box 482 carries a glass front 484 upon which the reading "small fire" appears. Signal 470 is housed in the box, and the box is partitioned at 486 to provide a chamber 488 in which I mount a lamp 490 for association with the circuit of the burglar side of the cabinet. The side of the glass associated with the lamp 490 is provided with the reading "quiet intruder," as indicated at 492. Thus lamp 490 and the signal 474 will be actuated in the same manner as the lamp 470 and the signal 474. In other words, lamp 490 and the signal 474 are actuated by the burglar circuit independently of the lamp 470 and the signal 474. Both sides of the cabinet are identical in construction and operation so that the operation of the burglar face 30

of the system will be readily understood. The one chief distinguishing feature lies in the substitution of an appropriate burglar closure of conventional design in each of the rooms.

In lieu of the battery 402 line current may be connected with the terminals 494 and 496. Terminal 494 is connected with a wire 498 connected with the wire 486, while the terminal 496 is connected with the wire 420.

I claim:

1. In a warning signal circuit having a plurality of self-opening switches and a plurality of self-closing switches arranged in vertically spaced groups: A pivotally mounted frame normally inclined to the vertical, arms of progressively shorter lengths in the direction of the pivotal axis of said frame and acting on said self-opening switches and said self-closing switches to normally hold the switches in closed and opened positions, respectively, a latch for holding said frame in its normal position, a solenoid for releasing said latch, and means for biasing said frame to an inoperative position for moving said arms away from said self-opening and self-closing switches.

2. The invention described in claim 1 wherein a manually actuated pivotal member coacts with said frame to move the latter to its normal position and into latched engagement with said latch.

DOCK R. WHEELER.
